UNITED STATES PATENT OFFICE

165,533

SUN GLASSES

Bert J. Lowres, East Orange, N. J.

Application September 19, 1951, Serial No. 16,681

Term of patent 3½ years

(Cl. D57—1)

To all whom it may concern:

Be it known that I, Bert J. Lowres, a citizen of the United States, residing at East Orange, in the county of Essex, and State of New Jersey, have invented a new, original, and ornamental Design for Sun Glasses, of which the following is a specification, reference being had to the accompanying drawings, forming a part hereof.

In the drawings:

Fig. 1 is a front elevational view; and

Fig. 2 is a top plan view of sun glasses embodying my new design.

I claim:

The ornamental design for sun glasses, as shown.

BERT J. LOWRES.
